The ornamental design for a flat panel display, as shown and described.

DESCRIPTION

FIG. 1 is a front perspective view of our design for a frameless electronic flat panel display;
FIG. 2 is a top view thereof;
FIG. 3 is a front view thereof;
FIG. 4 is a bottom view thereof;
FIG. 5 is a rear view thereof;
FIG. 6 is a left side view thereof;
FIG. 7 is a right side view thereof;
FIG. 8 is a bottom view of a second embodiment of our design, in which the front perspective, top, front, rear, left side, and right side views are the same as those in FIG. 1, FIG. 2, FIG. 3, FIG. 5, FIG. 6, and FIG. 7, respectively; and,
FIG. 9 is a rear view of a third embodiment of our design, in which the front perspective, top, front, bottom, left side, and right side views are the same as those in FIG. 1, FIG. 2, FIG. 3, FIG. 4, FIG. 6, and FIG. 7, respectively.

The stand represented by broken lines in FIGS. 1-9 is shown for environment only, and forms no part of the claimed design, and the broken lines shown in FIGS. 1 and 3 that are immediately surrounding the oblique lines are for the purpose of illustrating portions of the display panel.
